US00D936821S

(12) **United States Design Patent** (10) **Patent No.:** **US D936,821 S**
Rajput et al. (45) **Date of Patent:** **** Nov. 23, 2021**

(54) **SUCTION HOOD**

(71) Applicant: **ATLAS COPCO AIRPOWER,
NAAMLOZE VENNOOTSCHAP,
Wilrijk (BE)**

(72) Inventors: **Prashant K. Rajput**, Maharashtra (IN);
Vishal Krishnarao Patil, Maharashtra (IN); **Vijay Sohanlal Sharma**, Maharashtra (IN); **Srinivasan Arjune**, Tamil Nadu (IN)

(73) Assignee: **ATLAS COPCO AIRPOWER,
NAAMLOZE VENNOOTSCHAP,
Wilrijk (BE)**

(**) Term: **15 Years**

(21) Appl. No.: **29/731,407**

(22) Filed: **Apr. 15, 2020**

(30) **Foreign Application Priority Data**

Mar. 16, 2020 (EM) 007756754-0001

(51) **LOC (13) Cl.** **23-04**
